[57] CLAIM

The ornamental design for a stile for use primarily as part of a space divider frame, as shown and described.

DESCRIPTION

FIG. 1 is a fragmentary perspective view of a stile for use primarily as part of a space divider frame showing our new design, the broken lines showing frame surfaces are for illustrative purposes only and form no part of the claimed design;

FIG. 2 is a fragmentary front elevational view thereof; FIG. 3 is a top plan view thereof;

FIG. 4 is a fragmentary right side elevational view thereof;

FIG. 5 is a fragmentary left side elevational view thereof;

FIG. 6 is a top plan view of a second embodiment of a stile for use primarily as part of a space divider frame showing our new design; and,

FIG. 7 is a fragmentary rear elevational view thereof. The bottom of the stile for use primarily as part of a space divider frame is essentially the same in appearance as the top of the stile.
